ANTENNA BELT AND RADIO RECEIVER

Orrin G. Cafarella and James E. Votour,
Medford, Mass.

Application March 19, 1948, Serial No. 15,926

6 Claims. (Cl. 250—16)

1

This invention relates to a combination antenna belt and radio receiver, and pertains more particularly to portable radio receiving apparatus adapted to be worn on the person of the user in a comfortable, convenient and in conspicuous manner.

The principal purpose of our invention is to provide a small, light weight, compact and efficient personal radio receiving set, designed especially to be worn under the coat of a police officer, whereby the patrolman may, at all times, receive messages from police headquarters or other transmitting stations operated by the police force, without conspicuously disclosing to others that he is equipped with a radio receiver.

A particular object of the invention is to furnish a receiving set comprising an antenna belt in which the antenna wires and battery lead-wires are concealed and protected, and connected to terminals constituting elements of snap fasteners or other separable connections on the outside of the belt; an encased radio set preferably housed in a holster and having exterior terminals providing complementary fastener elements for attachment to certain of the belt terminals; and a second case preferably housed in a holster, containing batteries for operating the radio receiver and having exterior terminals providing complementary fastener elements for attachment to other terminals on the antenna belt.

Another object is to provide a radio receiver in which all of the operative parts are compactly and accessibly mounted on a rigid chassis housed in a shielding metal case, the encased chassis fitting in a leather holster and being detachably fastened to the antenna belt as aforesaid.

A further object is to provide an encased radio chassis which is rounded outwardly at its upper end, and a covering holster similarly rounded or beveled, and a holstered battery case also beveled outwardly at its upper end, so that the coat of the wearer will not display a sharp or conspicuous bulge when the apparatus is fastened to his belt.

A recommended embodiment of the invention is shown in the accompanying drawings, but it will be understood that the structural details of the apparatus herein illustrated and described may be varied without departing from the essence of this invention as defined in the appended claims. In the drawings,

Fig. 1 is a perspective view of a two-ply antenna belt and radio receiver, prepared in accordance with this invention, the plies of the belt being partially separated to indicate the normally concealed antenna and wiring;

Fig. 2 is a perspective view of the antenna belt with the plies stitched together, but with the receiver holster and battery holster detached from

2

the belt, to indicate the terminal-fastener elements;

Fig. 3 is a perspective view of the radio receiver, with the metal casing thereof partially removed from the chassis, and a portion of the receiver broken away;

Fig. 4 is a longitudinal section of the encased and holstered receiver, taken on line 4—4 of Fig. 5;

Fig. 5 is a transverse section on line 5—5 of Fig. 4;

Fig. 6 is a longitudinal section of the encased and holstered batteries, taken on line 6—6 of Fig. 7, one of the batteries being shown in elevation;

Fig. 7 is a transverse section on line 7—7 of Fig. 6; and

Fig. 8 is a fragmentary vertical section on line 8—8 of Fig. 7.

In the particular embodiment chosen for the purpose of illustration, the improved, personal radio receiving apparatus comprises, in general, the antenna belt 11 having inner and outer plies 12 and 13, respectively, and a conventional buckle 14 for fastening the belt around the waist of the wearer; a leather holster 15 containing the radio receiver case; a leather holster 16 containing the encased batteries for the receiver; a loop antenna 17 and battery wiring 18, carried on the inner side of the outer belt ply 13 (Fig. 1) and normally covered and concealed by the attached inner ply 12 (Fig. 2), connected to the receiver in holster 15 and to the batteries in holder 16; and an output wire 19 leading from the receiver through the back of holster 15 (Fig. 4) and to an ear-phone 20 carried by headset 20.

The loop antenna 17 may be cemented or otherwise attached to the back of the outer belt ply, and its ends are secured to a pair of terminals 21 suitably mounted in an insulated terminal plate 22 of thin fiber, plastic material or the like, said terminals extending through the outer belt ply and forming part of, or connected to, separable fastener elements such as the pair of socket parts 21' (Fig. 2) of a pair of snap fasteners. The wiring 18 is connected to the pairs of terminal 23 and 24 also mounted in the plate 22 and projecting through the belt ply to provide exterior snap sockets 23' and 24' respectively; and said wiring is also connected to complementary pairs of terminals 25, 26 and 27 on a second insulated terminal plate 28 carried by the belt ply 13. The terminal plates are relatively rigid for the secure attachment of the receiver case and the battery case to the aforesaid snap sockets, as hereinafter explained; and said plates, as well as the antenna and wiring are concealed when the two plies of the belt are marginally stitched together (Fig. 2) in a conventional manner.

The backs of the respective holsters 15 and 16 have openings exposing insulating plates 29 and 30

30 affixed to the metal cases therewithin. The exposed sides of the plate 29 has pairs of stud elements 31, 33 and 34 adapted to snap into the pairs of socket elements 21', 23' and 24' respectively; and the exposed side of the plate 30 has pairs of stud elements 35, 36 and 37 adapted to snap into the pairs of socket elements 25', 26' and 27', respectively. Said stud elements also constitute terminals for the radio receiver wiring and the battery wiring within the holsters 15 and 16, and the snap fastener attachments provide a detachable mechanical support for the receiver and battery cases contained in the respective holsters, as well as an electrical connection between the antenna and wiring between the plies of the belt, and the receiver and battery cases, respectively.

The attachment of the respective holsters 15 and 16 may be made additionally secure by providing encircling straps 38 and 39 having ends provided with socket elements 40 and 41 respectively, which engage upon stud elements 42 and 43 riveted to the outer belt ply. Several of said stud elements may be provided, as shown, to permit adjustment of the tension of the holster straps. Similar straps (not shown) having one end stitched to the belt and the other end buckled thereto on the opposite side of the holster, may obviously be used in place of the straps 38 and 39. The open, upper ends of the respective holsters are normally closed by snap-buttoned flaps 44 and 45 respectively.

Holster 15 contains, as aforesaid, the encased radio receiver (Figs. 4 and 5), comprising a chassis 46 of aluminum or other light metal, and a telescoping cover 47 of similar metal. The chassis consists of a flat back plate 48 having an integral end member 49, the side margins of the plate and end member being bent to form flanges 50 and 51 respectively. The cover 47 has a front 52, sides 53 formed with inturned flanges 54, a rounded upper end 55, and an open bottom end into which the chassis slides, as indicated in Fig. 3. The cover may be fastened in closed position by screws threading in openings 56 and 57 on the cover sides 53 and chassis end flanges 54. The cover 47 and the back plate 48 of the chassis constitute a case enclosing the elements of the receiving apparatus.

A shelf 58 is suitably mounted on the back plate 48 to provide mounts for the radio tubes and transformers of a conventional radio receiving set (for example, a four tube superheterodyne receiver), and also to provide an underlying wiring channels for wires leading to the terminals 31, 33 and 34 on the terminal plate 29 attached to the casing plate 48. Other elements of the receiver, such as the switch member 59, may be mounted on the end member 49 of the chassis. As the structural electrical details of the receiver are not essential to the present invention, they are illustrated somewhat diagrammatically, and need not be particularly described herein. It may be mentioned, however, that the variable condensers 60 and 61 may be adjusted by inserting a screwdriver through suitable openings 62 in the chassis end 49, without removing the casing 47 from the chassis; and that said openings may be normally closed by removable snap buttons 63. It will be understood that the switch lever 52 projects through the end flange 49 and also through a suitable opening in the bottom of the holster 15.

The encased chassis is inserted in the holster with the rounded end of the case uppermost, so

that said end (and the holster flap which rests thereon) curves outwardly and downwardly from the antenna belt, when the holstered receiver is attached thereto as previously explained. This formation softens any pronounced bulge in an officer's coat worn over the holster.

Holster 16 contains, as aforesaid, the encased batteries (Figs. 6-8), which include the A battery 64 and the B battery 65, housed in a metal case 66 having an opening exposing the terminals 35, 36 and 37 on the terminal plate 30 which is suitably mounted on the outside of the case 66. The battery leads are connected to appropriate terminals. Insulating plate 30 has more terminals than are required for the battery leads because the arrangement of the terminals on the plates 29 and 30, and the wiring between said plates, inside the belt, is preferably such that the receiver case and the battery case may be interchangeably attached to either of said terminal plates, thereby avoiding any confusion or mistake on the part of the user in connecting the holsters to the antenna belt. The top 67 of the case 66 is inclined outwardly and downwardly, so that the holster flap 45 resting thereon does not produce a pronounced bulge in the officer's coat.

A personally worn radio receiving set comprising the antenna belt, detachable receiver case and detachable battery case herein described, is simple and economical to manufacture and provides efficient and inconspicuous apparatus for the reception of radio messages by police officers and others whose duty or occupation requires a receiver satisfying the objects of this invention.

Various modifications are possible in the apparatus herein shown, within the scope of this invention; and it will be appreciated that the antenna belt may be worn outside the officer's coat when concealment of the apparatus is not essential. In such case, a shoulder strap may be suitably connected to the belt, if desired. It will also be appreciated that the leather holsters are not essential and may be omitted, if desired, for the metal cases containing the radio receiver and the batteries may be attached to the belt without the holsters and may be given a decorative exterior finish.

We claim:

1. Radio receiving apparatus of the character described, comprising a two-ply antenna belt having a pair of terminal plates disposed between its plies in spaced relation, each plate having terminals passing through the outer belt ply and formed exteriorly as elements of separable fasteners, an antenna disposed between the belt plies and connected to a pair of terminals on one of said plates, bridging wires also disposed between said belt plies and connected to complementary terminals on the respective plates, a radio receiver and a case enclosing the same, a set of batteries and a case enclosing the same, each of said cases having a terminal plate having terminals electrically connected to the receiver and batteries respectively, and the exposed portions of said terminals being formed as elements of separable fasteners adapted to engage the terminals of the respective terminal plates of said belt, whereby the encased receiver and the encased set of batteries may be mechanically and electrically connected to the antenna belt by engaging said fasteners.
2. Radio receiving apparatus of the character described, comprising a two-ply antenna belt having a pair of terminal plates disposed between

its plies in spaced relation, each plate having terminals passing through the outer belt ply and formed exteriorly as elements of separable fasteners, an antenna disposed between the belt plies and connected to a pair of terminals on one of said plates, bridging wires also disposed between said belt plies and connected to complementary terminals on the respective plates, a radio receiver and a holster enclosing the same, a set of batteries and a holster enclosing the same each of said holsters having an opening exposing a terminal plate having terminals electrically connected to the receiver and batteries respectively, and the exposed portions of said terminals being formed as elements of separable fasteners adapted to engage the terminals of the respective terminal plates of said belt, whereby the holstered receiver and the holstered set of batteries may be mechanically and electrically connected to the antenna belt by engaging said fasteners.

3. Radio receiving apparatus of the character described, comprising a two-ply antenna belt having a pair of terminal plates disposed between its plies in spaced relation, each plate having terminals passing through the outer belt ply and formed exteriorly as elements of separable fasteners, an antenna disposed between the belt plies and connected to a pair of terminals on one of said plates, bridging wires also disposed between said belt plies and connected to complementary terminals on the respective plates, a radio receiver and a holster enclosing the same, a set of batteries and a holster enclosing the same each of said holsters having an opening exposing a terminal plate having terminals electrically connected to the receiver and batteries respectively, and the exposed portions of said terminals being formed as elements of separable fasteners adapted to engage the terminals of the respective terminal plates of said belt, whereby the holstered receiver and the holstered set of batteries may be mechanically and electrically connected to the antenna belt by engaging said fasteners, said receiver comprising a chassis and a removable case therefor and said case having an inclined upper end, a case housing the set of batteries and having an inclined upper end, and the respective holsters having top flaps normally engaging said inclined case ends, whereby the tops of the holsters are inclined outwardly and downwardly when connected to said belt to avoid an abrupt bulge in an overhanging coat of the wearer of the belt.

4. Radio receiving apparatus of the character described, comprising a two-ply antenna belt having a pair of terminal plates disposed between its plies in spaced relation, each plate having terminals passing through the outer belt ply and formed exteriorly as elements of separable fasteners, an antenna disposed between the belt plies and connected to a pair of terminals on one of said plates, bridging wires also disposed between said belt plies and connected to complementary terminals on the respective plates, a radio receiver and a holster enclosing the same, a set of batteries and a holster enclosing the same each of said holsters having an opening exposing a terminal plate having terminals electrically connected to the receiver and batteries respectively, and the exposed portions of said terminals being formed as elements of separable fasteners adapted to engage the terminals of the respective terminal plates of said belt, whereby the hol-

stered receiver and the holstered set of batteries may be mechanically and electrically connected to the antenna belt by engaging said fasteners, each of the terminal plates in the belt having three pairs of complementary terminals, and the bridging wiring between said plates interconnecting corresponding pairs of said terminals, so that the holstered receiver and the holstered battery set are interchangeably applicable to said belt terminal plates.

5. Radio receiving apparatus of the character described, comprising a two-ply antenna belt having a pair of terminal plates disposed between its plies in spaced relation, each plate having terminals passing through the outer belt ply and formed exteriorly as elements of separable fasteners, an antenna disposed between the belt plies and connected to a pair of terminals on one of said plates, bridging wires also disposed between said belt plies and connected to complementary terminals on the respective plates, a radio receiver, a case therefor and a holster enclosing the same, a set of batteries, a case therefor and a holster enclosing the same, each of said holsters having an opening exposing a terminal plate mounted on the respective cases and having terminals electrically connected to the receiver and batteries respectively, and the exposed portions of said terminals being formed as elements of separable fasteners adapted to engage the terminals of the respective terminal plates of said belt, whereby the encased and holstered receiver and the encased and holstered set of batteries may be mechanically and electrically connected to the antenna belt by engaging said fasteners.

6. Radio receiving apparatus of the character described, comprising a two-ply antenna belt having a pair of terminal plates disposed between its plies in spaced relation, each plate having terminals passing through the outer belt ply and formed exteriorly as elements of the separable fasteners, an antenna disposed between the belt plies and connected to a pair of terminals on one of said plates, bridging wires also disposed between said belt plies and connected to complementary terminals on the respective plates, a radio receiver and a holster enclosing the same, a set of batteries and a holster enclosing the same, each of said holsters having an opening exposing a terminal plate having terminals electrically connected to the receiver and batteries respectively, and the exposed portions of said terminals being formed as elements of separable fasteners adapted to engage the terminals of the respective terminal plates of said belt, whereby the holstered receiver and the holstered set of batteries may be mechanically and electrically connected to the antenna belt by engaging said fasteners, the receiver having a switch lever projecting through the bottom of its holster.
